US00D355140S

United States Patent [19]

Yamamura

[11] Patent Number: Des. 355,140

[45] Date of Patent: ** Feb. 7, 1995

[54] ELECTRICAL MEASUREMENT METER

D. 342,690 12/1993 Jue et al. D10/103

[76] Inventor: **Kunio Yamamura**, 12-20, Magamoto
2-Chome, Urawa-shi, Saitama-ken,
Japan

Primary Examiner—Alan P. Douglas
Assistant Examiner—Antoine D. Davis
Attorney, Agent, or Firm—Darby & Darby

[**] Term: 14 Years

[57] **CLAIM**

[21] Appl. No.: 14,347

The ornamental design for an electrical measurement meter, as shown and described.

[22] Filed: Oct. 19, 1993
[52] U.S. Cl.

DESCRIPTION

[52] U.S. Cl. D10/100; D10/46
[58] Field of Search D10/46, 75, 78, 77,
D10/100, 102, 103, 123-127; D13/177; 116/20
R, 28.1, 35 R, 36, 51-54, 62.1-62.4, DIG. 33,
